(57) CLAIM

The ornamental design for a actuator element for a connecting terminal assembly, as shown and described.

DESCRIPTION

FIG. 1 is a perspective view of my design for actuating element for a connecting terminal assembly;

FIG. 2 is a side view of my design for actuator element for a connecting terminal assembly;

FIG. 3 is a top plan view of my design for actuator element for a connecting terminal assembly;

FIG. 4 is a bottom plan view of my design for actuator element for a connecting terminal assembly;

FIG. 5 is a left end view of my design for actuator element for a connecting terminal assembly; and,

FIG. 6 is a right end view of my design for actuator element for a connecting terminal assembly.
